TELEVISION TRANSMISSION SYSTEM

William A. Tolson, Erlton, N. J., assignor, by
mesne assignments, to Radio Corporation of
America, New York, N. Y., a corporation of
Delaware

Application July 16, 1930, Serial No. 468,221

3 Claims. (Cl. 178—6)

My invention relates to improvements in television transmission systems.

In using the conventional indirect or so-called "spot" scanning system for television transmission, it has been proposed, heretofore, to employ a lens-turret, in association with and forming part of the scanning apparatus, which includes the usual scanning disc or discs, to provide for rapid and convenient change or adjustment of the system for scanning objects located at different distances therefrom, or for varying the scanned area of an object at substantially a fixed distance from the apparatus to give the effect of the object being different distances from the apparatus as determined by the area scanned. The turret referred to carries a number of different lenses or lens systems which are moved selectively into operative position with respect to the associated disc or discs of the scanning apparatus upon rotation of the turret, the respective lenses or lens systems being effective to adapt the transmission system to different operating conditions, such, for example, as would be required to satisfactorily scan objects at widely varying distances from the system. As the lens-turret is rotated from one position to another, in the various constructions used heretofore, a very unpleasant condition develops at the receiver for the reason that the picture is placed completely out of focus as one lens is moved out of operating position and is again brought back into focus as another lens is moved into operating position.

With the foregoing in mind, one of the objects of my present invention is to provide an improved television transmission system wherein the same is rendered ineffective for transmission upon movement of the lens or other structure to adapt the system to different operating conditions such as that of distance of the object from the scanning apparatus.

In accordance with my invention, suitable means are provided for rendering the television transmission system ineffective for transmission, such means operating automatically for this purpose upon movement or adjustment of the means or structure provided for adapting the system to different operating conditions.

Further in accordance with my invention, a television transmission system is automatically rendered ineffective for transmission upon displacement of the lens structure associated with the scanning apparatus in adapting or adjusting the same for scanning objects at different distances therefrom.

More particularly in accordance with my invention, suitable switch means are associated with an electrical circuit forming part of a television transmission system and are operable to render the same ineffective for transmission, the lens-turret forming part of the scanning apparatus, which includes the usual scanning disc or discs, being so co-related with the switch means that the latter is controlled in accordance with the rotary movement of the turret in adjusting the scanning apparatus for objects at different distances therefrom.

My invention resides in the system and apparatus of the character hereinafter described and claimed.

For the purpose of illustrating my invention, one embodiment thereof is shown in the drawing, in which

Fig. 1 is an elevational view, partly diagrammatic, of a system embodying my invention;

Fig. 2 is an elevational view, looking toward the left in Fig. 1; and

Fig. 3 is a fragmentary view similar to Fig. 1, illustrating a modification.

The reference numeral 10 designates a lens-turret, of well-known construction used in scanning apparatus for a television transmission system, and includes a base member 11 supported for rotary movement about an axis 12 and carrying a plurality of different lenses or lens systems 13, 14, 15, and 16, the latter being moved selectively into operative association with the other parts or units such, for example, as the usual scanning means herein conventionally illustrated as a disk 23 of the Nipkow type provided with a series of spirally arranged apertures 24. When the various lenses forming the lens system are moved into cooperative association with the scanning disk element, for example, these various lenses are effective to adapt the system for scanning objects at different distances therefrom.

A photo-cell amplifier of any suitable construction, and which includes the usual B battery 17 and forms part of the television transmission system, is indicated generally by the reference numeral 18. A switch 19 of any suitable construction is connected as shown in the battery circuit, the arrangement being such that when the switch is closed such circuit is completed, and the system effective for transmission. As is well known, when switch 19 is open, the system will be ineffective for transmission.

A plurality of pins 20 are carried by the base 11 of the turret and are disposed for engagement with the switch 19, as shown in Fig. 1, to close

the same when the adjacent lens or lens system is in operative position with respect to the scanning disc or discs of the scanning apparatus of which such lens then forms a part. The action is, therefore, such that the system is effective for transmission only when the turret has been rotated or displaced to place one of the lenses in operating position.

Upon displacement of any lens, or more specifically, upon rotary movement of the turret to change from one lens to another to adapt the system for scanning objects at different distances therefrom, the pin 20 which previously engaged switch 19 to hold the same closed is moved out of engaging relation with the same to permit opening thereof by its own spring action. The system is then ineffective for transmission.

From the foregoing it will be seen that the present improvements provide that during change or adjustment of the system to adapt the same to different operating conditions, the system is controlled in such manner as to eliminate any undesirable effects or influences which might otherwise develop during such change, the system being automatically restored for normal operation when the desired change has been effected.

While the present system or apparatus disclosed as representing one embodiment of my invention is, specifically, a structural arrangement for rendering the same ineffective for transmission by controlling a photo-cell amplifier forming part of the system, such control being made during change or adjustment from one lens or lens system to another in the scanning apparatus, it is to be understood that my invention is of much broader adaptation, the broadest aspect being automatic control of a television system in any desirable manner during change or adjustment thereof for the purpose of adapting the same to different operating conditions, the said control providing for elimination of undesirable effects which might otherwise develop during such change or adjustment.

In the specific embodiment of my invention disclosed, it is to be understood that various changes might be made without departing from the spirit of my invention or the scope of the claims. For example, the arrangement might be as shown in Fig. 3, wherein a switch 19a, corresponding to switch 19 in Fig. 1, is biased by its own spring action to closed position and is connected across the amplifier 18 to short-circuit the same, the engagement of the pins 20 with the switch operating to open the same and thus to render the television system effective for

transmission only when one of the lenses is in operating position with respect to the disc or discs of the scanning apparatus of which it is then a part.

I claim as my invention:

1. In a television system, a scanning system for converting light values on successive elemental areas of a subject of which an image is desired into proportional electrical representations thereof, a lens turret holding a series of lens elements usable individually for focusing the subject upon the scanning system, and means cooperating with the lens turret for rendering the scanning system operative only at time periods when one of the series of lens elements is in operative relationship with respect to the scanning system.

2. In television transmission apparatus, a scanning system for converting light values on successive elemental areas of a subject of which an electro-optical image is desired into proportional electrical representations thereof, a lens turret associated with the scanning system, said lens turret comprising a base member supported for rotary movement and including a plurality of individual lens units each of a different focal length supported parallel to the axis of rotation and disposed concentrically about said axis for movement into and out of operating association with the scanning means so as to focus the optical image thereupon, and means cooperating with the lens turret for rendering the scanning system operative only at time periods when one of the series of individual lens elements is in operative relationship with respect to the scanning system so as to focus the optical image of the subject thereupon.

3. In a television transmission system, a scanning system for developing picture signals, a lens turret comprising a series of individual lens units each of different focal length and each individually cooperable with said picture signal developing means to form a component part thereof, means for effecting relative movement between the lens units and the picture signal developing means to render the latter effective selectively to produce signals of subjects located at different distances therefrom, and means operable to render the picture signal developing system ineffective for transmission during time periods within which different units of the turret are being placed in cooperative relationship with respect to the scanning means.

WILLIAM A. TOLSON.
